UNITED STATES PATENT OFFICE

146,820

DESIGN FOR A TOY HIGH CHAIR

William P. Zegel, New York, N. Y., assignor to
Molded Products Company, New York, N. Y.,
a copartnership composed of Leslie S. Steinau,
Leslie Steinau, Jr., and Irving Reader

Application April 11, 1946, Serial No. 128,480

Term of patent 3½ years

(Cl. D34—15)

To all whom it may concern:

Be it known that I, William P. Zegel, a citizen of the United States, residing in New York, in the county of Bronx and State of New York, have invented a new, original, and ornamental Design for a Toy High Chair, of which the following is a specification, reference being had to the accompanying drawing, forming a part thereof.

Fig. 1 is a perspective front view of a toy high chair showing my new design;

Fig. 2 is a side view thereof; and

Fig. 3 is a rear view.

I claim:

The ornamental design for a toy high chair, substantially as shown.

WM. P. ZEGEL.
